No. 831,676.

PATENTED SEPT. 25, 1906.

A. M. MCLERAN.

COMBINATION WIRE WORKING TOOL.

APPLICATION FILED OCT. 27, 1905.

UNITED STATES PATENT OFFICE.

ALVORD M. McLERAN, OF KANSAS CITY, MISSOURI.

COMBINATION WIRE-WORKING TOOL.

No. 831,676.

Specification of Letters Patent.

Patented Sept. 25, 1906.

Application filed October 27, 1905. Serial No. 284,623.

To all whom it may concern:

Be it known that I, ALVORD M. McLERAN, a citizen of the United States, residing at Kansas City, in the county of Jackson and 5 State of Missouri, have invented certain new and useful Improvements in Combination Wire-Working Tools, of which the following is a specification.

The present invention is an improvement 10 on my patent for a combination wire-working tool, No. 777,126, issued December 13, 1904; and one of my objects is to provide a tool combining most of the advantageous features embodied in said patent with certain new elements hereinafter described and 15 claimed.

A further object is to produce a tool which may be manufactured more cheaply than the one disclosed in the above-mentioned patent 20 without sacrificing its efficiency or durability.

In order that the invention may be fully understood, reference will now be made to the accompanying drawings, in which—

Figure 1 represents a side elevation of the 25 tool with the outer ends of its handles broken away. Fig. 2 is a longitudinal section of same, taken on line II II of Fig. 3, showing the tool open in full lines and closed in dotted lines. Fig. 3 is a transverse longitudinal 30 section taken on line III III of Fig. 1, and Fig. 4 is an edge view of the tool.

In carrying out the invention I employ a pair of exterior heads 1 of circular form provided with integral arms 2, which extend 35 rearwardly and form one of the tool-handles. Said circular heads are reinforced at their margins with inwardly-extending flanges 3 and 4. The flanges on one head abutting against the flanges on the opposing head 40 leave an intervening space 5 for a purpose hereinafter specified. Heads 1 and their arms 2 are rigidly secured together by means of rivets 6, 6^a, and 6^b and a centrally-disposed transverse pin 7, having reduced terminals 8 extending through bosses 9, formed 45 integral with the central portions of heads 1 for the purpose of reinforcing the latter.

10 designates a pair of oppositely-disposed splicing-jaws extending transversely through 50 heads 1 and communicating with the peripheries thereof through open slots 11. The

widths of the latter are less than the diameter of the jaws.

12 designates U-shaped recesses in the front central portions of heads 1, and 13 designates clamping-jaws at the rear ends of the 55 enlarged portions 2^a of arms 2, which latter are strengthened with a reinforcement 14.

15 designates registering longitudinal slots in the enlarged portions 2^a, each of which has 60 an edge containing a series of segmental recesses 16.

17 designates a staple-pulling jaw located between the forward portions of heads 1, to which latter it is rigidly secured by rivet 6^b. 65 Said jaw is provided with a cutting edge 19, extending into recess 12, and a shoulder 17^a, which abuts against the edges of the adjacent flanges 3, and thus relieves rivet 6^b of a portion of the strain to which it is subjected 70 when the jaw is in use.

20 designates an interior head of irregular form fitting snugly in space 5 and pivotally mounted upon transverse pin 7, the shoulders 8^a of which latter abut against the inner 75 sides of bosses 9, and thus prevent the central portions of heads 1 from binding against head 20 sufficiently to render the operation of the latter difficult, flanges 3 and 4 serving the same purpose near the peripheries of the 80 heads. Head 20 is provided with a pair of diametrically opposite splicing-jaws 21 of segmental form, which register with jaws 10 when the tool is open, as shown in Figs. 1 and 2. Jaws 21 communicate with the peripheries of the head 20 through open slots 22, which, like slots 11, are of less width than the 85 diameter of the jaws.

23 designates a staple-pulling jaw formed integral with the forward end of head 20 and 90 provided at one side with a cutting edge 24. Jaw 23 and cutting edge 24 are similar in shape and coöperate with jaw 17 and cutting edge 19 in pulling staples or cutting wire. The staple-pulling jaws will also answer the 95 purpose of a pair of pliers.

25 designates a shank having an enlarged portion 26, formed integral with the rear end of head 20. Said enlarged portion 26 is provided with a clamping-jaw 27, adapted to co-operate with clamping-jaw 13, and a triangular slot 28, the reduced end 29 of which is 100

adapted to register with the rear end of slot 15 when the tool is closed. The latter is held in a closed or partly-closed position when gripping an object by means of a key 30, 5 slidably arranged in slots 15 28 and provided with shoulders 31, which engage the inner surfaces of portions 2^a, and thus retain the key in position between said portions. The reduced ends 32 of the key extend slightly 10 beyond the outer surfaces of portions 2 and form a convenient grip for the thumb and index-finger when it is desired to slide the key either backward or forward in the slots. When the key occupies the forward position, 15 (shown by full lines, Fig. 2,) the width of the forward end of slot 28 permits the tool to be opened and closed at will. When said key is moved backwardly to the dotted position in said figure, the tool will be held in a closed 20 position. Likewise if a wire or other object is grasped by any of the jaws of the tool the latter may be held in a closed position on said wire or other object by pushing the key backwardly in the slots as far as possible, and thus 25 leave both hands of the operator free. After the key has been adjusted to a certain position it is held from accidental movement by reason of its reduced ends 32 being forced into engagement with the registering recesses 16 by means of a flat spring 33, secured 30 at its forward end to the rear portion of head 20 and bearing at its opposite end against reinforcement 14, so that it will normally push said members apart, as shown by full lines, 35 Fig. 2. The opening movement of the tool is limited by a shoulder 34 on head 20 contacting with rivet 6^a.

35 designates a handle secured to shank 25 by means of rivets 36.

40 Having thus described my invention, what I claim, and desire to secure by Letters Patent, is—

1. In a tool of the character described, two heads pivotally secured together and provided with jaws, slotted portions extending from said heads, the slot in one of said portions being triangular, and a key slidably arranged in said slotted portions adapted when slid in one direction to hold the jaws in either 50 a closed or partly-closed position.

2. In a tool of the character described, two heads pivotally secured together and provided with jaws, slotted portions extending from said heads, one edge of one of the slots 55 having segmental recesses, a key slidably arranged in said slotted portions adapted when slid in one direction to hold the jaws in a closed position, and means interposed between the slotted portions for normally holding them apart and for forcing the key into engagement with said segmental recesses.

3. In a tool of the character described, two heads pivotally secured together and provided with staple-pulling jaws, slotted por-

tions extending from said heads, one edge of 65 one of the slots having segmental recesses, a key slidably arranged in said slotted portions adapted when slid in one direction to hold the jaws in a closed position, and means interposed between the slotted portions for 70 normally holding them apart and for forcing the key into engagement with said segmental recesses.

4. In a tool of the character described, a head composed of two members secured together and provided with jaws, a second head arranged in a space between the two members and pivotally secured to the latter, said second head also having jaws which coöperate with those on the first-mentioned head, 80 slotted portions on said heads, and a key slidably arranged in said slotted portions adapted when slid in one direction to hold the jaws in either a closed or partly-closed position.

5. In a tool of the character described, a 85 head having jaws and a centrally-disposed space, a second head arranged in the space and pivotally secured to the first-mentioned head, said second head also having jaws which coöperate with those on the first-men- 90 tioned head, slotted portions formed integral with said heads the slotted portions of the first-mentioned head having a space for the reception of the second head, handles extending from the slotted portions, a key slidably 95 arranged in the intermediate slotted portion provided with shoulders which abut against the outer slotted portions, and reduced terminals on said key which project through said slotted outer portions, substantially as 100 described.

6. A tool of the character described consisting of a head formed of two members secured together and provided with jaws, abutting flanges extending inwardly from the 105 margins of said members and leaving a space between the latter, a handle extending from said members, an irregular-shaped head snugly fitting the space between the two members and pivotally secured to the latter, 110 jaws on said irregular-shaped head which coöperate with those on the first-mentioned head when the tool is open, and a handle extending from the irregular-shaped head.

7. A tool of the character described consisting of a head of circular form composed of two members secured together and provided at their forward ends with registering U-shaped recesses, inwardly-extending abutting flanges formed integral with the margins 120 of said members and leaving a space between the latter, a staple-pulling jaw secured between said members and projecting into the U-shaped recesses, a handle formed integral with said members, an irregular-shaped head 125 snugly fitting the space between the two members and pivotally secured to the latter, a staple-pulling jaw formed integral with

said irregular-shaped head and adapted to co-
operate with the first-mentioned jaw, a han-
dle secured to said irregular-shaped head, a
spring interposed between the handles adapt-
ed to normally hold the staple-pulling jaws
5 open, and means slidingly arranged in the
handles for holding the jaws closed.

In testimony whereof I affix my signature
in the presence of two witnesses.

ALVORD M. McLERAN.
